ADJUSTABLE ELECTRODE SUPPORT FOR
ELECTRON DISCHARGE TUBES

Arthur K. Wing, Jr., Nutley, and Lyle A. Backer, Denville, N. J., assignors to Federal Telephone and Radio Corporation, New York, N. Y., a corporation of Delaware

Application April 4, 1946, Serial No. 659,606

8 Claims. (Cl. 250—27.5)

1

This invention relates to electrode mountings, and particularly to mounting arrangements for electrodes used in vacuum tubes.

The principal object is to provide an effective electrode mounting which is adjustable to permit easy alignment of the electrodes.

An ordinary form of vacuum tube comprises an evacuated envelope containing a number of electrodes which are mounted in spaced relationship to each other. The mounted positions of the electrodes relative to each other are usually of considerable importance. The three-electrode form of vacuum tube, for example, may comprise a cathode, an anode spaced from the cathode, and a grid between the cathode and anode. In such an arrangement, it is important that the spacing of all parts of the electrodes relative to each other shall be accurately adjusted and maintained.

Owing to manufacturing variations, it is often desirable or necessary to adjust the positions and alignments of one or more of the electrodes manually by provision of adjustable mounting means; and such mounting means for this purpose have heretofore been proposed. These former expedients have permitted partial adjustment of the electrodes relative to each other, but they have not permitted a full adjustment for both the distance apart and the tilt of the electrodes.

According to our present invention, we provide adjustable mounting means whereby a full adjustment of an electrode may be made both with respect to distance apart and for the tilt. We carry this out by supporting the electrode to be adjusted by a mounting member or support provided with an arcuate portion whose radius of curvature is centered at a point relative to which it is desired to position and tilt the electrode. For holding the mounting member in position, we provide a clamping means within which the arcuate portion is held, this clamping means being provided with a corresponding arcuate surface to permit movement of the arcuate mounting member portion relative to the clamping member.

The arrangement is such that movement of the arcuate mounting portion relative to the clamping member provides adjustment for the tilt. The clamping means itself is made adjustable in a sideways direction so as to provide for the sideways adjustment. By the combination of these adjustable means, the desired adjustment both for the distance apart of the electrodes and for the tilt is taken care of.

The foregoing and other features of our invention will be better understood from the following detailed description and the accompanying drawing of which:

Fig. 1 is an elevation view, partially in cross section, of parts of a vacuum tube showing the mounting of a tube electrode according to our invention; and

2

Fig. 2 is a cross-sectional view taken from the top at line 2—2 of Fig. 1.

In the drawings there are shown the electrodes of a three-electrode vacuum tube having a centrally located filament type cathode 1 centered on a longitudinal axis A—A, a cylindrical form of grid 2 around the cathode and a cylindrical anode 3 around the grid. Only part of the tube envelope 4 is shown, as it forms no part of the invention. The centrally located filamentary type cathode 1 is held in its central position by the two supporting rods 5 and 6 which act as the terminal leads of the filament and are carried down through the base of the tube in any well known and suitable manner, not shown in the drawing. The particular mounting means for the anode is not shown, as the only purpose for showing the anode in the drawing is to indicate its position relative to the other electrodes.

The cylindrical shaped control grid 2 is mounted in accordance with our invention. The grid support is a conical member 7 fastened to the lower edge of the grid at the upper edge of the cone at 8, which fits just inside the grid and may be fastened by suitable means such as welding. The depending cone 7 is bent at a circular position 9 to form an annular flange 10; and the flange 10 is shaped in the form of a segment of a sphere with the radius of curvature at a point P at about the central position of the axis of the filament.

Clamping means are provided to hold the flange 10 of the conical support. The clamping means are in the form of a pair of annular rings 11 and 12, which are formed with a pair of corresponding surfaces 13 and 14, also shaped as segments of spheres having their radii of curvature centered at the same point P as the spherical center of flange member 10. The arrangement is such that the flange 10 fits between the spherical surfaces of ring members 11 and 12, as shown in Fig. 1, so that the flange can be held between the two rings.

For the purpose of holding this grid assembly in its desired fixed position, there is provided a supporting collar 15 which may be of a conventional form provided according to a common practice with cylindrical protrusions 16 and 17 tapered to thin edges and adapted to provide a seal with the glass envelope 4, as shown. The exterior part 18 of the collar 15 extends through the envelope and is available for making electrical contact with the grid.

The inner periphery 19 is drilled and threaded at several places around its circumference to receive fastening screws 20 which pass through holes 21 and 22 of the clamping rings 11 and 12, and through corresponding holes 23 of the flange 10.

60 To provide for adjustment of the grid mounting

means, all the holes 21, 22 and 23 are made somewhat larger than the diameter of the screws, as shown in Fig. 2. Since the positions of the screws are fixed by the screw holes in flange 15, the oversize dimensions of the holes in the clamping members permit adjustment in the horizontal direction, that is, in any direction perpendicular to the axis A—A of the electrode structure. In this way, the central axis of the cylindrical grid can be made to coincide with the axis A—A of the filament. In spite of the ability to shift the grid in this direction, the axis of the grid may still remain on something of a tilt with respect to the axis and the filament. This tilt can be overcome by shifting the position of the flange 10 relative to the clamping means 11 and 12. This shift is readily accomplished by moving the segmental flange 10 a little bit about the axis P, and the provision for making this adjustment is provided by the oversize dimension of the hole 23 through the flange.

By this arrangement, adjustment for both the tilt of the grid electrode and of its distance from the filament electrode in a sideways direction may readily be accomplished. When the adjustment is finally made, it is held by tightening down the screws 20.

While our invention has been particularly described in connection with a cylindrical grid electrode, it will be understood that it is equally applicable to other electrodes in the tube which it is desired to hold in a particular relative position. Furthermore, the invention is not limited to use with cylindrical electrodes, but may also be used for positioning and supporting electrodes having other shapes. The invention accordingly, should not be construed to be limited to the arrangement shown in the drawings, but only as limited by the appended claims.

We claim:

1. Means for supporting an electrode comprising a support for the electrode, a flange attached to the support, said flange being in the shape of a spherical segment centered about a point with reference to which it is desired to position the electrode, and clamping means for holding the flange, said clamping means having surfaces in the form of spherical segments centered about the same point, and means holding the flange between said surfaces.

2. Means for supporting an electrode comprising a support for the electrode, said support having a portion in the form of a part of a sphere whose radius of curvature is centered about a point with reference to which it is desired to position the electrode, and a clamping means having a surface in the form of a portion of a sphere also centered about the same point, and means holding the spherical portions together.

3. An electrode support comprising an annular flange shaped in the form of a segment of a sphere which is centered about a point with reference to which it is desired to position the electrode, a clamping ring having a surface in the form of a spherical segment having the same radius of curvature as the first-mentioned spherical segment, said spherical segments being capable of being moved relative to each other and means clamping the two spherical segments together.

4. An electrode support, having an annular flange in the shape of a segment of a sphere, a pair of clamping rings each having a surface in

the form of a spherical segment whose center of curvature is at the same point as the center of curvature of the first-mentioned segment and means clamping the flange between the spherical segmental surfaces of the two clamping rings.

5. An electrode support having a supporting member in the shape of a segment of a sphere, a pair of clamping devices each having a clamping surface in the form of a spherical segment whose center of curvature is at the same point as the center of said sphere, means adjustably positioning the member between the spherical segmental surfaces, and means clamping the member between the clamping surfaces and holding the clamping devices in a fixed position.

6. An electrode support having an annular flange in the shape of a segment of a sphere, a pair of clamping rings each having a surface in the form of a spherical segment whose center of curvature is the same point as the center of curvature of the sphere, a fixed supporting member, and fastening means attaching the clamping rings to the fixed member, said clamping rings having oversize holes through which the fastening means pass and said annular flange having oversize holes through which the clamping means also pass, said flange being held between the surfaces of the clamping rings whereby the clamping rings may be moved relative to the fixed supporting member and the flange may be moved relative to the clamping rings.

7. An electrode support comprising a conical supporting member attaching to the electrode, said supporting member having a flange in the form of a segment of a sphere, a pair of clamping rings each having a surface in the form of a spherical segment whose center of curvature is at the same point as the center of curvature of the sphere, said flange being placed between the surfaces of the clamping rings, a fixed supporting member, and fastening devices attached to the fixed supporting member and passing through holes through the rings and the flange, said holes being oversize with respect to the fastening means whereby the flange may be moved relative to the rings and the rings may be moved relative to the fixed supporting member to provide adjustment of the position and the tilt of the electrode.

8. Means for supporting a cylindrical type of grid in a position around a cathode located within the grid, said means comprising a support for the grid having an annular flange in the shape of a segment of a sphere, a pair of clamping rings each having a surface in the form of a spherical segment whose center of curvature is at the same point as the center of curvature of the sphere, a fixed supporting member and fastening means attaching the clamping rings to the fixed member with the flange sandwiched between the segmental surfaces of the clamping rings, said clamping rings and annular flange having oversize holes through which the clamping means pass, whereby the clamping rings may be moved in a direction perpendicular to the longitudinal axis of the grid within the limits of the oversize holes in the rings to adjust the distance of the grid from the cathode, and the flange may be moved relative to the ring surfaces to the limit of the oversize hole of the flange to adjust the tilt of the grid.
